UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

FASTENER.

Application filed March 8, 1921. Serial No. 450,750.

To all whom it may concern:

Be it known that I, FRED S. CARR, a citizen of the United States, and a resident of Newton, in the county of Middlesex and 5 Commonwealth of Massachusetts, have invented an Improvement in Fasteners, of which the following description, in connection with the accompanying drawings, is a specification, like characters on the drawings representing like parts.

This invention pertains to improvements in separable fasteners. It is among the objects of the invention to provide a fastener of simple construction in which a superior 15 resistance to undesired separation when under lateral strain is provided.

In the drawings, which show a preferred embodiment of my invention:—

Figure 1 is an elevation of two pieces of 20 fabric held together by a preferred form of fastener;

Fig. 2 is a section on the line 2—2 of Fig. 1, being partly in elevation;

Fig. 3 is a front elevation of the preferred form of socket; and

Fig. 4 is a front elevation of the preferred form of stud illustrated in Fig. 2.

Referring to the drawings and to the preferred form of my invention selected for 30 illustrative purposes, I have shown a fastener comprising a resilient stud cooperating with a socket having a stud-receiving aperture therein, the stud-receiving aperture being narrowed in at least one direction to

35 provided against undesired separation of stud and socket by the resolution of forces arising from lateral strain between stud and socket. In the illustrated construction, the socket is adapted to be sewn to its carrying

40 fabric and is springless, being a simple plate 5 having a stud-receiving aperture 6 which is narrowed toward one side as by the notch 7. Stitch-receiving apertures 8 are provided. The socket is preferably, as illustrated, flat and is very thin because it need not be provided with the usual upturned spring-retaining flange. The preferred form of stud illustrated is adapted to be attached to the stud-carrying fabric 10 by

50 stitches 11 extending through stitch-receiving apertures 12, and is provided with a head portion 13 and a neck portion 14. The head is preferably resilient. This resiliency may be provided in any suitable way, but I prefer 55 to provide it by slitting the head so that

the stud may be formed from a single piece of metal, avoiding the complexities of the usual "bird-cage" type of resilient stud. It will be understood, however, that any resilient stud, including the usual "bird-cage" 60 type, may be used to advantage in connection with my invention. The preferred form of stud illustrated is provided with two slots transverse to its axis and preferably at right angle to each other. These slots 20 and 21 65 preferably extend into the base 22 of the stud a sufficient distance so that the resiliency principally arises from flexing of portions of the stud base. The stitch-receiving apertures are preferably, as illustrated, located out of line with the slits in the base before described, so that the stud base need not be unduly increased in diameter to provide strength.

When the stud is entered in the socket and 75 strain between them is exerted in a direction tending to urge the neck of the stud toward the narrowed portion 7 of the stud-receiving aperture in the socket, the stud will shift laterally in the socket a slight distance, enough to prevent separation of stud 80 and socket by any resolution of forces likely to arise from normal lateral strains. This shifting will not, however, be sufficient to prevent separation of stud and socket by 85 strain exerted in a separating direction at an angle greater than that likely to arise from the resolution of forces under lateral strains between stud and socket. The socket is preferably attached to the socket-carrying fabric 90 30 with the notch or narrowed portion 7 toward the edge of the fabric, this being the direction of normal lateral strain between stud and socket.

While I have shown and described a preferred form of one embodiment of my invention, it will be understood that changes involving omission, substitution, alteration and reversal of parts, and even changes in the mode of operation, may be made without departing from the scope of my invention, which is best defined in the following claims.

Claims:

1. A separable fastener comprising a resilient stud having a head and a neck smaller than said head; a stud receiving aperture of less width than the normal transverse diameter of said head and having a narrowed extension at that side thereof in which the 110

lateral strain between the stud and socket is normally exerted and into which the neck of the stud may shift laterally sufficiently to prevent disengagement of the stud from the socket under the resolution of forces arising from lateral strain, the width of such narrowed extension being less than that of said neck to limit the extent of entrance of said neck thereinto and sufficiently wide to 10 permit such shifting movement of the neck thereinto to lock the stud and socket against separation by normal lateral strains, while sufficiently narrow to permit disengagement thereof when separating force is applied in 15 a direction substantially transverse to the normal line of lateral strain.

2. A separable fastener comprising, in combination, a stud having a resilient head capable of collapsing laterally to a limited extent; and a socket providing a stud-receiving aperture; said aperture having a narrowed portion of a size partly to receive the neck of the stud; said narrowed portion extending in the direction of normal lateral strain between the stud and socket; the width of the narrowed portion and also the transverse diameter of the aperture being less than the width of the resilient head whereby the head must collapse laterally 20 when it is forced into the aperture; said narrowed portion providing means whereby separation of stud and socket arising from normal lateral strain is prevented, whereas such separation is permitted, even though 25 the stud and socket are under lateral strain, when strain is exerted in a separate direction.

3. A separable fastener comprising, in combination, a stud having a resilient head

generally circular in cross-section, and a 40 socket presenting a relatively flat face having a stud-receiving aperture therethrough and a notch communicating with said aperture of less width than the normal diameter of said head and arranged to permit the 45 stud to shift laterally in said aperture under normal strains, whereby to oppose separation of the stud and socket by resolution of forces resulting therefrom, said notch permitting only such limited entrance of the 50 neck of the stud therein as will admit of separation of the head from the socket when strain is exerted at an angle greater than that arising from the resolution of forces under such normal strains, at an angle 55 greater than that arising from the resolution of forces under lateral strain between the stud and socket.

4. A socket for separable fasteners formed from a single sheet of metal so as to be flat 60 and reversible, said socket having a centrally arranged and generally circular stud-receiving aperture therein presenting a shallow rounded notch at one side thereof, said notch being arcuate and of less radius than the aperture and its center being offset relative to the center of the aperture, and means whereby the socket may be attached to a fabric. 65

5. A socket for separable fasteners formed from a single sheet of metal, having stitch-receiving apertures therethrough and having a generally circular stud-receiving aperture therein, presenting a shallow notch at 70 one side thereof said socket flat and reversible. 75

In testimony whereof, I have signed my name to this specification.

FRED S. CARR.
